AUTOMOBILE TRUNK

Michael G. Dietrich, Rathdrum, Idaho

Application May 7, 1932, Serial No. 609,889

3 Claims. (Cl. 224—29)

This invention relates to trunks and more particularly to a trunk adapted to be mounted on a motor vehicle or the like.

An object of this invention is to provide a trunk or article carrying case which is so constructed that it can be used to carry articles of various sizes and particularly articles having a length in excess of the depth and width of the trunk.

10. Another object of this invention is to provide a trunk of this kind which has a swingable rear wall structure for extending the rear wall so that relatively large articles may be carried within the trunk body which is not possible with a trunk having a fixed capacity.

A further object of this invention is to provide in a trunk of this kind releasable locking means for locking the trunk in its extended position as well as when closed.

20. A still further object of this invention is to provide a swingable rear wall structure which can be either raised or lowered depending on the size of the articles which it is desired to place in the trunk, the lowering of the rear wall permitting articles of a length greater than the extended portion of the trunk to be carried thereby.

Still another object of this invention is to provide a trunk having an extensible bottom which is slightly elevated toward the rear, thus keeping articles longer than the trunk when extended, from working backward.

The invention will be described in detail in the accompanying description and illustrated in the drawings, wherein:

Figure 1 is a detail perspective view of a trunk constructed according to the preferred embodiment of this invention in open position.

Figure 2 is a sectional view taken substantially through the center of the trunk and showing the trunk in extended position.

Figure 3 is a sectional view taken on the line 3—3 of Figure 2.

Figure 4 is a fragmentary sectional view taken on the line 4—4 of Figure 1.

Figure 5 is a fragmentary sectional view taken on the line 5—5 of Figure 1.

Figure 6 is a fragmentary sectional view taken on the line 6—6 of Figure 2.

50. Referring to the drawings wherein like numerals of reference designate corresponding parts throughout the several views, the numeral 10 designates generally a trunk body comprising a bottom wall 11, a rear wall 13, and end walls 12.

55. A lid or cover 14 is hingedly carried by the rear

wall 13 and is maintained in open position by means of a slotted link 15. This link 15 is pivotally carried by a bracket 16 mounted on an inwardly extending flange 17 carried by the rear wall 13, and an L-shaped bracket 18 is mounted on the lid 14 and provided with a headed pin 19 loosely disposed in the L-shaped slot 20 provided in the link 15. Through the provision of this L-shaped or angular slot 20, the lid 14 can be maintained in upright or open position, as desired.

The lid 14 is provided with marginal flanges 20a which extend about the outer surface of the end walls 12 and the front wall 21. This front wall 21 is hinged at the lower edge thereof, as at 22, to the forward edge of the bottom 11, and at each end the front wall 21 is provided with angular members 23 which have one leg thereof riveted, as at 24, to the front wall 21 and the other leg is adapted to slidably engage the outer surface of the end wall 12.

An inner end wall 25 is secured to the front wall 21 and is slidable within the end wall 12 and provided with an upper inwardly extending flange 26 having an aperture 27 adjacent the forward end thereof within which a locking pin 28 carried by a releasable locking lever 29 is adapted to be disposed. A spring 30 carried by the inwardly extending flange 17 engages the lever 29 so as to constantly urge this lever 29 into locking position.

The front wall 21 has an inwardly extending flange 31, which cooperates with the flanges 17 and 26 in providing a reinforcing rim for the walls of the trunk 10.

A pivoted wall 32 is pivoted as at 33 to the inwardly extending flange 31 and when the trunk is in collapsed position as shown in Figure 1, the pivoted wall 32 will be dependably disposed closely adjacent the front wall 21. In this manner, the trunk, as shown in Figure 1, can be filled with the desired articles and the pivoted wall 32 will not take up undue space within the trunk body.

In order to provide means whereby the trunk 10 may be releasably locked in open or extended position, I have provided a locking means including a resilient bar 34 which is riveted or secured, as at 35, to the inner end wall 25 and is provided with a reverted end portion 36 which is adapted to engage in a slot or opening 37 provided in the outer end wall 12 when the forward wall 21 is lowered, as shown in Figure 2. This locking member 34 prevents forward movement of the front wall 21 and the inner end walls 25 beyond the opening 37.

A releasable locking member 38 is secured, as

at 39, to the inner end wall 25 above the holding member 34 and is provided with an outwardly extending locking pin 40 engageable in an opening 41 provided in the outer end wall 12, so that when 5 the forward portion of the trunk is in its extended position, it will be releasably locked and cannot be collapsed or moved into the position shown in Figure 1 until the locking bar 38 is released through the medium of a pivoted releasing member 10 10 42 which is carried by the end wall 25.

This releasing member 42 is provided with a tapering end portion 43 and a lug 44 at the end oppositely from the tapering portion 43, this lug 44 providing an operating means for swinging the 15 releasing lever 42. The tapering portion 43 is adapted to engage between the resilient locking bar 38 and the inner end wall 25 and movement of this tapering portion 43 toward the rivets 39 or fixed end portion of the resilient bar 38 will cause 20 the locking member 38 to be moved inwardly and carry the locking pin 40 out of the aperture 41.

When the forward wall 21 is in the position shown in Figure 2, the pivoted wall 32 may be left in either horizontal position or may be swung 25 in vertical position, as shown in Figure 2, and in this position is releasably locked by means of a resilient locking member 45 having an outturned end portion 46 engaging the inner surface of the pivoted wall 32, the locking member may be 30 pressed outwardly toward the end wall 25 and in this position, the extension 46 will be positioned in an opening 46a in the wall 25, and the wall 32 may then be swung inwardly. The flange 26 is provided with an inwardly extending pin 47 and 35 the pivoted wall 32 has an aperture adjacent each end thereof to receive this pin 47 and when the wall is engaged with this pin 47, the inner end walls 25 will be held against spreading. It will, 40 of course, be understood that the lid for the trunk, when it is in its extended position, will be normally maintained in open position by the bar 15, but it can be lowered even though the trunk is in its extended position, better allowing a canvas hood over the entire trunk to keep out rain and dust.

45 In the use of this device, when the trunk is in its collapsed position, as shown in Figure 1, it may be filled with desired articles, and the trunk can be provided with suitable locking means, not shown, so as to lock the trunk in this position. 50 Preferably, the wall 13 is inclined to the vertical a slight degree, this being desirable where the trunk is mounted on a vehicle having a body so shaped as to require the wall of the trunk to be inclined so as to fit snugly against the rear of 55 the machine. When it is desired to carry articles which are of the size that they cannot be carried within the trunk in its collapsed position, as shown in Figure 1, the forward wall 21 can be swung downwardly by pressing the locking lever 29 upwardly so as to depress the locking pins 28 and 60 permit the inner walls 25 to move with the forward wall 21.

The use of the pivoted wall 32 is optional, depending on the character of the articles to be 65 placed within the extended trunk as, if desired, this pivoted wall 32 can be left in substantially horizontal position or can be raised and locked in its upraised position through the medium of the locking member 45, and the locking pins 47 70 will engage in the apertures provided adjacent each end of the wall 32, so as to prevent spreading of the inner or extensible end walls 25. As the forward wall 21 is swung downwardly, the locking bars 34 and 38 will engage in the apertures 37 75 and 41, respectively, so as to releasably lock the

ends 25 of the trunk in the extended position of the trunk.

When it is desired to again collapse the trunk, the releasing levers 42 may be swung upwardly so as to carry the locking pins 40 out of the apertures 41, and due to the inclination of the locking portion 36 of the locking bar 34, the forward wall 21 can be raised and when the forward wall 21 is substantially vertical, the upper end portion 44 of the releasing members 42 will strike 10 the wall 13 and swing the releasing lever 42 out of engagement with the locking member 38, thereby permitting this locking member 38 to again move into locking position upon lowering 15 of the wall member 21.

It is, of course, understood that various changes and modifications may be made in the details of construction and design of the above specifically described embodiment of this invention without departing from the spirit thereof, 20 such changes and modifications being restricted only by the scope of the following claims.

What is claimed is:—

1. A trunk as set forth, comprising a trunk body including side and end walls, a bottom wall 25 and a hinged closure, means for hingedly mounting one of the side walls to the bottom wall for movement outwardly into extended horizontal position, inner end walls carried by the hinged side wall for movement therewith, releasable locking means carried by said inner end walls and engaging the first named end walls to releasably lock the inner end walls and the hinged side wall in extended position, a second hinged side wall, means for hingedly mounting said second hinged side wall on said first side wall, releasable locking means for locking said second hinged side wall in substantially vertical position when said first hinged side wall is in extended 30 horizontal position, a lock releasing means for said first mentioned locking means, and releasable locking means carried by the other side wall of the trunk body and engaging the inner end walls for releasably locking the first hinged side wall in collapsed position. 35

2. A trunk as set forth, comprising a trunk body including side and end walls, a bottom wall and a hinged closure, means for pivotally mounting one of said side walls to an edge of said bottom wall, inner end walls fixedly carried by said hinged side wall, flanges carried by said inner end walls, releasable locking means for releasably locking the inner end walls and the hinged side wall in substantially horizontal extended position, a pivoted releasing member 50 for the locking means, a flange carried by the upper edge of said hinged side wall, a second side wall hingedly carried by said flange of said hinged side wall, releasable locking means carried by the inner end walls for releasably locking the second hinged side wall in vertical position when said first hinged side wall is in extended horizontal position, means carried by the inner wall flanges and engaging the second hinged side wall to prevent spreading of the inner end walls when in extended position, and means carried by the other side wall of the body and engaging the inner wall flanges to releasably lock the hinged side walls and inner end walls in collapsed position. 55

3. A trunk as set forth, comprising a trunk body including side and end walls, a bottom wall and a hinged top, means for pivotally mounting one of the side walls on the bottom wall for movement of said one side wall into horizontal 60 position, inner end walls carried by the hinged side wall for movement therewith, releasable locking means carried by the inner end walls and engaging the second hinged side wall to prevent spreading of the inner end walls when in extended position, and means carried by the other side wall of the body and engaging the inner end walls to releasably lock the hinged side walls and inner end walls in collapsed position. 65

position, inner extensible end wall members carried by said one side wall whereby to provide extensible end walls, means engaging said latter end wall members and said first end walls to releasably lock said one side wall and extensible end walls in extended position, a lock releasing means carried by one of the inner end walls for releasing said locking means, a second locking

means for locking said one side wall in upright position, said means including an apertured flange carried by an inner end wall, a flange carried by the other side wall, and a spring pressed locking member mounted on said second flange and engageable in said aperture of said inner end wall flange. 5
